(57) **CLAIM**

The ornamental design for the cable plug protector assembly, as shown and described.

DESCRIPTION

FIG. 1 is a top view of a first half of the cable plug protector assembly, shown removed from the fasteners and second half, to show aspects of the design that are not visible when combined, the second half being identical;

FIG. 2 is a bottom view thereof;

FIG. 3 is a front view thereof;

FIG. 4 is a rear view thereof;

FIG. 5 is a left side view thereof;

FIG. 6 is a right side view thereof;

FIG. 7 is a top, right side isometric view thereof;

FIG. 8 is a top, left side isometric view thereof;

FIG. 9 is a bottom, left side isometric view thereof;

FIG. 10 is a bottom, right side isometric view thereof; and,

FIG. 11 is an isometric view of the cable plug protector assembly.
